UNITED STATES PATENT OFFICE.

HAZEL MANN MONTEALEGRE, OF IOLA, KANSAS.

DEVICE FOR SHAPING THE UPPER LIP.

Application filed March 25, 1922. Serial No. 546,846.

To all whom it may concern:

Be it known that I, HAZEL M. MONTEALEGRE, citizen of the United States, residing at Iola, in the county of Allan and State of Kansas, have invented a new and useful Device for Shaping the Upper Lip, of which the following is a specification.

This invention relates to devices for reshaping the upper lip of a person, and has for its object the provision of a simple and easily applied device to re-shape the upper lip of a person to conform to what is known as the "Cupid's bow," whereby it is unnecessary to resort to a surgical operation to produce this effect.

A full and complete understanding of the invention may be obtained from a consideration of the following detailed description, taken in connection with the accompanying drawing forming a part of this specification; it being understood that while the drawing shows a practical form of the invention, the latter is not to be confined to strict conformity with the showing thereof, but may be changed or modified, so long as such changes or modifications mark no material departure from the salient features of the invention, as specifically pointed out in the appended claims.

In the drawing:

Fig. 1 discloses the head of a person with my improved lip shaping device connected to the upper lip;

Fig. 2 is a fragmentary view in horizontal section of the lip-forming means;

Fig. 3 is a longitudinal section of the device about to be applied to an upper lip;

Fig. 4 is a longitudinal section of the same with the device applied in shaping relation to an upper lip.

Fig. 5 is a view in perspective of a modification of my improved lip shaping device.

Referring to the drawing, 1 indicates a body member having guides 2 and 3, in which is slidably mounted a spring member re-bent upon itself at an intermediate point, as shown at 4^a, to form two arms 4 and a loop, to which is attached an operating handle 5, the re-bent portion 4^a of the spring member being inserted through a slot 6 in one end of the operating handle 5. The guide 2 is spaced from the body member a greater distance than the guide 3.

The outer free ends 7 and 8 of the spring member diverge outwardly, so that as they are drawn within the guide 2 formed on the

end of the body 1, by an outward pull on the handle 5, the inclined sides of the guide 2 will tend to draw the free ends 7 and 8 closer together to cause the pads or jaws 9 and 10, preferably formed of rubber and respectively located on said free ends of the spring member, to grip and contract the central portion of the lip at opposite points and cause a depression in the lip, as shown in Fig. 4. When the jaws 9 and 10 are properly clamped on the lip, an eccentric lever 11 pivotally mounted in a bracket 12 on the body 1, will cause the eccentric 13 to grip the spring arms 4 and maintain them in place, when the free end of the lever is moved downwardly and rests upon the guide 3.

Upon the outer end of the base plate 1 is provided a matrix or former conforming to the shape of a lip of the well-known type of Cupid's bow, and it comprises flaring spaced members 14 and 15, provided with curved concave grooves 16 merging centrally of the former into an opening 17. The upper lip is adapted to be forced into the grooves and maintained in shaping relation with the same when the jaws 9 and 10 are locked on the upper lip by a gentle pull on the handle 5. The arms 4 and the jaws 9 and 10 are locked in this position by the lever 11. As shown in Figs. 2, 3 and 4, the spring member is adapted to be reciprocated through the opening 17 provided in the end of the body 1 and between the flaring members 14 and 15 of the matrix or former.

In applying the device to the upper lip, the lever 11 having been released from its locking position with the spring member, the handle 5 is moved inwardly causing the jaws 9 and 10 to move outwardly from the matrix or former, so that the diverging ends 7 and 8 of the spring member will move apart by reason of the resiliency of the arms of the spring member, and also by reason of the fact that the opening 17 is flared outwardly. The jaws are spread sufficiently apart so that jaw 10 will engage the underside of the upper lip, while the jaw 9 engages a directly opposite point on the upper edge of the upper lip and centrally of the bow of the lip. The handle 5 is then gently pulled rearwardly whereby the jaws 9 and 10 will grip the upper lip as the free ends 7 and 8 of the spring member are drawn toward each other by reason of said ends

moving inwardly through the flaring opening 17, while the lip itself is drawn inwardly into the curved concave grooves 16 of the outwardly flared members 14 and 15 of the matrix, as shown in Fig. 2. The bail 11 is then locked on the arms 4.

By my new and improved device, I not only cause a depression to be formed in the upper surface and centrally of the upper lip, but the upper lip will be drawn into shaping relation with the matrix whereby the upper lip will eventually be changed to the form of the wellknown Cupid's bow.

In the modification disclosed in Fig. 5, 15 upon the base member 1^a is pivotally mounted a clamping member 18 having a manipulating thumb piece 19 pressed upwardly by means of a coil spring 20 which is connected between the thumb piece 19 and the outer 20 end 21 of the base member 1^a, the outer end of the base member being enlarged for the purpose.

The other end of the base member 1^a is bifurcated, thereby forming two arms 22 25 and 23, and between which the clamping member 18 is pivoted on the pin 24.

Upon the outer ends of the arms 22 and 23 of the base member are formed right and left lip forming members 14^a and 15^a, which 30 together provide a matrix conforming to the shape of a lip of the well known type of Cupid's bow. The curved lip clamping portion 27 of the clamp 18 is adapted to be oscillated between the lip forming members 14^a and 15^a and force the central portion 35 of the lip between the said members 14^a and 15^a and form a depression in the lip which is typical of the well known form referred to above.

40 The lip forming members 14^a and 15^a are connected to the reduced portion of the arms 22 and 23 and extend upwardly at substantially right angles to said arms, having their greatest height adjacent the arms 22 and 23 45 and receding outwardly towards their ends in a materially reduced portion conforming to the portions of the lips which are adjacent to the corners of the mouth.

In applying the modified form disclosed 50 in Fig. 5 to the upper lip, the thumb piece 19 is depressed, thereby raising the curved lip gripping portion 27, whence the members 14^a and 15^a are pressed firmly against the upper lip while the thumb piece 19 is released, 55 causing the curved lip gripping portion 27 of the clamp 18 to depress the central portion of the lip in the space located between the lip forming members 14^a and 15^a. Sufficient applications of the device to the upper 60 lip will produce a lip of the well known type described as Cupid's bow.

What is claimed is:—

1. A device for shaping the upper lip of a person, comprising a matrix and a clamping means adapted to grip the lip inside and

outside at opposite points and centrally of the bow of the lip, said clamping means being movable to draw the lip into the matrix.

2. A device for shaping the upper lip of a person, comprising a matrix and a clamping means adapted to grip the lip inside and outside at opposite points and centrally of the bow of the lip, said clamping means being movable to draw the lip into the matrix, and means for locking the clamping means 75 in the position to which it has been moved.

3. A device for shaping the upper lip of a person, comprising a matrix conforming to the shape of the lip desired, a pair of jaws adapted to grip the lip between them, 80 and means for moving the jaws nearer to each other and at the same time moving them both toward the matrix.

4. A device for shaping the upper lip of a person, comprising a body, a pair of jaws 85 slidably mounted on said body and adapted to grip opposite sides of the lip and form a depression in said lip, and a matrix on the end of the body conforming to the shape of the lip desired, said jaws being adapted to 90 maintain the lip in the matrix for re-shaping the lip.

5. A device for shaping the upper lip of a person, comprising a body, a pair of jaws 95 slidably mounted on said body and adapted to grip opposite sides of the lip and form a depression in said lip, a matrix on the end of the body conforming to the shape of the lip desired, said jaws being adapted to maintain the lip in the matrix and cooperating 100 with the matrix for re-shaping the lip, and means on the body for locking the jaws in gripping relation with the lip.

6. A device for shaping the upper lip of a person, comprising a body, guides, a 105 spring member slidable in the guides, clamping jaws mounted on the free ends of the spring member and engaging a lip at opposite points, and a matrix conforming to the shape of the lip desired, said spring member being adapted when moved in the guides to cause the jaws to grip and indent the lip and force the same into the matrix.

7. A device for shaping the upper lip of a person, comprising a body, a spring member 115 slidable on the flared clamping jaws mounted on the free ends of the spring member and engaging a lip at opposite points, and a matrix conforming to the shape of the lip desired, said clamping jaws adapted when moved by the spring member to indent the lip and force the same into the matrix on the body, said spring means having inclined sides whereby when the flared jaws are moved towards the matrix the jaws will 120 be closed upon the lip.

8. A device for shaping the upper lip of a person, a body, a pair of spring arms connected together at one end and slidably on the body, clamping jaws mounted on the 125 130

- free end of the arms and adapted to engage the lip at opposite points, means for moving the jaws in gripping relation with the lip when said arms are moved along the body, a matrix conforming to the shape of the lip desired and cooperating with the slidable jaws to draw the lip into the matrix whereby said lip is depressed centrally thereof and shaped to the form of the matrix.
- 5 9. A device for shaping the upper lip of a person, a body, a pair of spring arms connected together at one end and slidable on the body, clamping jaws mounted on the free end of the arms and adapted to engage the lip at opposite points, means for moving the
- 10 15
- jaws in gripping relation with the lip when said arms are moved along the body, a matrix conforming to the shape of the lip desired and cooperating with the slidable jaws to draw the lip into the matrix, whereby said lip is depressed centrally thereof and shaped to the form of the matrix, and means for locking the arms in position on the body when the jaws are in engagement with the lip.
